DESIGN FOR A DRESS

Margaret Michelson, New York, N. Y.

Application August 4, 1937, Serial No. 70,833

Term of patent 3½ years

To all whom it may concern:

Be it known that I, Margaret Michelson, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein

The characteristic feature of my design resides in the combination on the dress disclosed of the cordings on the waist portion and sleeves, in the manner shown.

I claim:

The ornamental design for a dress, substantially as shown and described.

MARGARET MICHELSON.
